CLAIM

The ornamental design for a product packaging, as shown and described.

DESCRIPTION

The patent or application file contains at least one drawing executed in color. Copies of this patent or patent application with color drawing(s) will be provided by the Office upon request and payment of the necessary fee.

FIG. 1 is a top, front, left perspective view of a product packaging showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an enlarged view of FIG. 2 thereof; and,

FIG. 9 is an enlarged view of a portion of FIG. 8.

The uneven length broken lines immediately adjacent to the shaded area are imaginary lines that define the bounds of the claimed design and form no part thereof. The even length broken lines immediately adjacent to the shaded area define the bounds of the claimed design and form no part thereof. The unshaded regions within or adjacent to the shaded areas form no part of the claimed design. The even length broken

(Continued)

lines depicting the remainder of the product packaging show features that form no part of the claimed design.
